UNITED STATES PATENT OFFICE.

JOSEPH W. WEST, OF BEARDEN, ARKANSAS.

PERPETUAL CALENDAR.

Application filed May 9, 1922. Serial No. 559,538.

To all whom it may concern:

Be it known that I, JOSEPH W. WEST, a citizen of the United States, residing at Bearden, in the county of Ouachita, State of Arkansas, have invented certain new and useful Improvements in Perpetual Calendars; and I do hereby declare the following to be a full, clear, and exact description of the invention, such as will enable others skilled in the art to which it appertains to make and use the same.

This invention relates to new and useful improvements in calendars, and particularly to perpetual calendars.

One object of the invention is to provide a calendar which will display the month, day, and date, and which is easily and simply adjustable for each month of the year.

Another object is to provide a calendar of this character wherein are arranged two relatively movable sheets, one of which has sight openings through which may be seen the name of the month, together with the numbers of days in the months, and the dates and days of each month, means being provided to be set for the first day of the year, which will govern the dates of the remaining months, said means being arranged to be set at the beginning of each year.

Other objects and advantages will be apparent from the following description when taken in connection with the accompanying drawing.

In the drawing:

Figure 1 is an elevation of a calendar made in accordance with the invention.

Figure 2 is an elevation of the inner sheet of the calendar, showing the arrangement and grouping of the various elements which make up the calendar.

Referring particularly to the accompanying drawing, 10 and 11 represent a pair of strips of material of the desired length and width, the strips being connected at their upper ends to a pair of flexible strips of suitable material 12. The strips 12 are engaged over the lower horizontal member or bar of the elongated wire loop 13, said loop having an eye 14, in the center of its upper portion or bar, for engagement on a nail, or like fastening, to support the calendar on a wall.

Printed, or otherwise formed on the sheet 11, and in the longitudinal center thereof, are two lines of month names, as indicated at 15, and in the outer sheet 10 there is

formed a longitudinal opening 16, of a width equal to the width of the double column of month names. Printed along the margins of the opening 16, at distances equal to the distances of the month names longitudinally of the columns, are the initials or abbreviations of the days of the week, beginning with Sunday, at the upper end of the opening, and ending with Saturday, at the lower end. Removably engaged on one edge of the opening 16, is a marking member 17, which is arranged to be placed over one of the day initials, and the strip 10 moved longitudinally of the strip 11, to dispose the marker opposite January, thus indicating that the first day of January falls on the day of the week indicated by the marker.

In the lower portion of the outer strip 10 there is formed a large rectangular sight opening 18, and printed on the sheet 11, to be seen through this opening, are numbers indicating the month dates. The numbers are so arranged that when the strip 10 is moved longitudinally of the strip 11, a complete group of numbers representing thirty-one days, will appear in the opening. Each time the sheet 10 is moved the numbers line up differently with the initials of the days of the week, which are printed along the vertical margins of this opening 18.

In using the calendar, the marker 17 is placed at the day of the week on which the first day of the year falls, as for instance, the present year, 1922, the first day was Sunday. After placing the marker at the first initial at the upper end of the opening 16, the sheets 10 and 11 are then moved longitudinally with respect to each other, until the marker is opposite the desired month, as for instance the present month, April. Then, upon reference to the grouping of numbers seen through the lower opening 18, it will be seen that there is a full complement of numbers for the month of April with the first of the month falling on Saturday.

The calendar is adaptable for perpetual use, the only change being in the moving of the marker for the first day of the year, which will be one more for each succeeding year. In a leap year, after the twenty-ninth of February has passed, the marker is moved down one space, as will be understood, so that the dates will properly follow for the rest of the year.

The sheets are preferably heavy paper of the desired texture, while the strips 12 are formed of some cloth material, such as muslin, or the like, to permit the same to easily slide over the bar of the loop. Under each month name is printed the number of days in that particular month, February showing twenty-eight days.

What is claimed is:

- 10 1. A perpetual calendar including a strip having a pair of sight openings each having day symbols at its margins, a movable indicator removably engaged on one edge of one of said sight openings and adapted for 15 disposition over any one of the day symbols to indicate the first day of a given year, and a second strip movable relatively to the first strip and having a month name group visible through the first sight opening and a date 20 group visible through the other sight opening, the month names being positionable opposite the said indicator, the date group disposed on the second strip, with relation to the month name group, that upon positioning any month name opposite the indicator the proper portion of the date group will be disposed within the said other sight opening.
- 25 2. A calendar comprising a pair of relatively movable strips one of which has a pair 30 of sight openings each having week day

symbols at its side, a support for the strips, a flexible member connecting the strips and slidable on the support, the other strip having month names visible through one of the sight openings and month dates visible 35 through the other sight opening, and a marker movable along one side of the first sight opening for disposition over a day symbol and opposite a month name to govern the positions of the strips relatively to each 40 other for each month of any year.

3. A calendar comprising a pair of relatively slidable strips one of which is formed with a pair of sight openings, week-day symbols at the sides of each sight opening, 45 month names on the other strip visible through one sight opening, month dates on said other strip visible through the other sight opening, a loop support, flexible strips connecting the corresponding ends of the 50 first strips and slidable on the support, and a marker slidably engaged with the sight opening strip and at one side of the month name sight opening thereof.

In testimony whereof, I affix my signature, in the presence of two witnesses.

JOSEPH W. WEST.
